UNITED STATES PATENT OFFICE.

WALTER P. OSGOOD, OF MALDEN, MASSACHUSETTS, ASSIGNOR TO BOSTON MACHINE WORKS COMPANY, OF LYNN, MASSACHUSETTS, A CORPORATION OF MASSACHUSETTS.

CEMENTING MACHINE.

Application filed August 19, 1920. Serial No. 404,643.

To all whom it may concern:

Be it known that I, WALTER P. Osgood, a citizen of the United States, and resident of Malden, county of Middlesex, Commonwealth of Massachusetts, have invented an Improvement in Cementing Machines, of which the following description, in connection with the accompanying drawings, is a specification, like characters on the drawings representing like parts in each of the several views.

This invention relates to cementing machines for applying cement to shoe parts, such as quarters, and other more or less like uses. More particularly the invention has to do with a double or duplex cementer adapted to apply cement simultaneously upon two material surfaces opposite one another, such as the edges of two quarters placed back to back. A principal object of the invention is to provide improved means for applying and distributing the cement upon the upper material surface to receive the cement. A further object is to provide an improved form of cement laying rollers adapted to distribute and apply the cement more effectively than has been done with those hitherto in use. To these ends I provide means co-operative with a lower cement roll for directing and influencing the cement to flow directly upon the upper cement receiving surface and employ the upper roll as a distributing instrumentality serving to spread and press the cement evenly upon the upper material surface. In accordance with my invention the operative surface of the rolls is provided with diagonally disposed teeth or ridges adapted to direct and influence the flow of the cement over all parts of the receiving surfaces. The foregoing and other objects and advantages of the invention will more fully appear from the following detailed description, and the distinctive features of novelty will be thereafter pointed out in the appended claims.

Referring to the drawings:

Fig. 1 is an elevation showing the operative portion of a cementing machine embodying the invention, the body of the machine including the main cement reservoir being broken away;

Fig. 2 is an end view looking from the left in Fig. 1;

Fig. 3 is a plan view of the lower cement roll with its mounting and showing the cement wipe-over and gauge member which

constitutes an important feature of the invention;

Fig. 4 is a partial end view similar to Fig. 2 but showing the application of material in the machine; and

Fig. 5 is a bottom plan view of the cement wipe-over and gauge member detached.

10 indicates a part of the body and cement reservoir of a cementing machine which may be of usual and previously known type, such for example as shown in my prior application Serial No. 273,099 filed January 25, 1919. This machine body is equipped with a tubular extension or horn 11 into which extends a shaft 12 bearing at its end a lower cement applying roll 13, the major portion of which is enclosed by the horn 11 but which has an upper operative portion exposed above the horn. A combined work 15 table and cement gauge 14 is mounted for adjustment upon a flattened top surface of the horn, this adjustment being effected by a screw 15 equipped with a knurled head 15^a, and determining the amount of cement 20 which is supplied by the roll 13, generally as set forth in my said prior application. 16 indicates an arm mounted to swing from a pivot at the rear of the machine body and bearing a rotary driven shaft 17 on the end 25 of which is mounted an upper cement distributing and feed roll 18 as more fully shown in said prior application. As shown the arm 16 terminates some distance from the roll 18 and the projecting end portion of the shaft 17 has bearing in a block 19 borne by a stout rod or bar 20 adjustably clamped in a socket of the arm 16 by means of a clamp screw 21. This block 19 fits up closely 30 against the inner side of the roll 18 and it is equipped with an extension 19^a bearing a cement deflector and roll retaining plate 22 which extends inward at the front of the roll 18, preferably tapering to a point approximately coincident with the center of the roll 35 18 as best seen in Fig. 2. This plate 22 fitting up closely against the front of the roll 18 serves in co-operation with the block 19 to hold the roll 18 in the adjusted position in which it may be set, the block with the 40 roll being clamped from endwise displacement by the screw 21. The lower roll 13 takes up cement from the interior of the horn 11 and applies it to the lower material surface M, it being understood that the horn 45 is kept supplied with cement up to a predetermined level by suitable means, which

50 55 60 65 70 75 80 85 90 95 100 105 110

may be similar to those shown in my said prior application. For applying cement to the upper material surface M, I provide an auxiliary roll or inward extension of the 5 lower roll 13 as indicated at 23, this roll being fixed upon the shaft 12 adjacent the roll 13 so as to be in the nature of an inward extension thereof. This roll 23 is formed with a toothed periphery adapted to take up 10 cement from the horn, the teeth thereof being shown however as parallel with the roll axis, while the teeth of the roll 13 are inclined for a purpose to be explained. For co-operation with this roll 23 I provide a 15 cement wipe-over member 24 which constitutes also a work gauge as will appear. This member 24 is adjustably clamped to the top of the horn 11, for this purpose having its inner end formed with an elongated slot 20 24^a through which pass clamp screws 25. This member is formed with a wall 24^b fitting the periphery of the roll 23 and extending forward diagonally in the direction of roll movement, this wall hence serving to 25 gather the cement from the roll 23 and influence it to move outward and toward the material. Back of this wall 24^b the member 24 is formed with a pocket space or inverted valley 24^c expanding outward in the 30 direction of cement delivery, the other side of this valley being formed by a straight wall 24^b which fits down closely upon the flat top of the table 14. The member 24 is formed at the extremity of the straight wall 35 portion 24^d with a curved notch or groove 24^e which serves as an edge guide for the material, and projecting diagonally upward and forward from this groove is a prong 24^f, which constitutes a top guide for 40 the material. The cement flows from the inverted valley 24^c upon the top face of the work thus guided, and tending to follow the direction of travel of the work, it forms into a wave preceding the engagement of the distributing and feed roll 18. The material is 45 held correctly aligned for this cement distribution by the prong 24^f in connection with the notch 24^e which co-operatively serve as guides for the material. As the material 50 with the top surface thereof thus supplied with cement passes between the rolls 13 and 18, the upper roll 18 besides co-operating to feed the work forward, also serves to distribute and spread the cement evenly and uniformly 55 upon the material. For this purpose I have found that an arrangement of teeth inclined as shown at 18^a, upon the periphery of the roll is desirable and advantageous, the direction of the incline of these 60 teeth being such as to influence the cement inward or toward the edge of the material whereby an adequate and uniform coating is insured. It is to be noted that the rolls 13, 18 are slightly tapered so as to present a 65 wider opening for the work at the outer

sides, than at the inner sides thereof as indicated at X, this being desirable for attaining uniformity in the spreading of the cement upon material such as skived quarters and the like. The lower roll 13 preferably also 70 has teeth inclined as shown for the purpose of influencing the cement inward thereof. In connection with this feature the gauge edge of the table 14 which co-operates with the roll 13 is cut out farther toward the 75 outer portion of the roll 13 as indicated at 26 so as to permit a relatively greater quantity of cement to be taken up by the outer portion of the roll 13 to be influenced and worked inward by the diagonal teeth upon 80 engagement with the material. The series of teeth on the rolls 13, 18 are preferably gashed or notched at intervals circumferentially of the rolls for the purpose of obtaining a better hold upon the material in feeding 85 the same through the machine. It will be understood that suitable means (not shown) will be provided for causing the upper roll 18 to press upon the material to the requisite degree for feeding the material, 90 and suitable means, shown as an adjusting screw 27 borne by the arm 16 and engaging the top of the body 10, is provided for limiting the approach of the roll 18 to the roll 13, 95 I am aware that the invention may be embodied in other specific forms without departing from the spirit or essential attributes thereof, and I therefore desire the present embodiment to be considered in all respects as illustrative and not restrictive, 100 reference being had to the appended claims rather than to the foregoing description to indicate the scope of the invention.

Having described my invention, what I claim as new and desire to secure by Letters' 105 Patent is:

1. Apparatus for applying cement, comprising material feeding means, unidirectional moving means associated therewith for taking up cement from a body of cement, and relatively stationary means adapted to gather the cement so taken up and arranged to direct and spread the same upon a surface of the material to be coated in advance of the engagement of said feeding means therewith.

2. Cement applying apparatus, comprising co-acting rolls equipped for feeding material between them, one of said rolls having a mounting to take up cement from a body of cement and applying the same to one material surface, means associated therewith for taking up additional cement, and relatively stationary means arranged to direct the cement so taken up upon another material surface to be coated.

3. Cement applying apparatus, comprising co-acting rolls equipped for feeding material between them, one of said rolls having a mounting to take up cement from a body 120

of cement and applying the same to one material surface, means associated therewith for taking up additional cement, and relatively stationary means arranged to direct the cement so taken up upon another material surface to be coated, said stationary means constructed and equipped to serve also as a material guide.

4. Cement applying apparatus, comprising material feeding means, rotatable means associated therewith for taking up cement on its periphery from a cement body, and a relatively stationary cement director arranged to gather the cement so taken up and direct the same upon a surface to be coated, said cement director constructed and arranged to serve also as an edge guide for the material.

5. Cement applying apparatus, comprising material feeding means, means associated therewith for taking up cement from a cement body, and a relatively stationary cement director arranged to receive the cement so taken up and direct the same upon a surface to be coated, said cement director constructed and arranged to serve also as an edge guide for the material and having an inclined prong projecting therefrom serving as a top guide for the material and also to influence the cement to flow thereupon.

6. Cement applying apparatus, comprising a pair of co-active rolls for feeding material, one of said rolls receiving cement from a cement body and adapted to apply the same directly to a material surface, said roll having associated therewith another roll portion adapted to take up other cement, and a relatively stationary cement director receiving the cement so taken up from said roll portion and influencing the same to flow upon a second material surface to be coated, another one of said co-active feed rolls serving to distribute the cement so applied to said second material surface.

7. Cement applying apparatus, comprising a pair of co-active feed rolls, one thereof extending into a body of cement and adapted to apply the cement directly to one material surface, and having another roll portion mounted to rotate therewith and also taking up cement, a relatively stationary cement director constituting also a material

guide adapted to receive the cement from said roll portion and direct the movement thereof upon another material surface, the other one of said feed rolls serving to distribute and spread the cement so applied to said second material surface.

8. Cement applying apparatus, comprising a pair of co-active feed rolls, one thereof extending into a body of cement and adapted to apply the cement directly to one material surface, and having another roll portion mounted to rotate therewith and also taking up cement, a relatively stationary cement director constituting also a material guide adapted to receive the cement from said roll portion and direct the movement thereof upon another material surface, the other one of said feed rolls having its periphery equipped with inclined teeth adapted to influence and distribute evenly the cement so applied to said second material surface.

9. Cement applying apparatus, comprising a pair of co-active feed rolls having an equipment for applying cement upon two material surfaces simultaneously, both of said rolls having their peripheries formed with inclined teeth for distributing and equalizing the application of cement upon said surfaces.

10. Cement applying apparatus, comprising a pair of co-active feed rolls, one thereof mounted to extend into a body of cement and having its periphery formed with inclined teeth for the purpose stated, and means associated with said roll for directing cement therefrom upon a material surface.

11. Cement applying apparatus, comprising a pair of co-active feed rolls, one thereof mounted to extend into a body of cement and having its periphery formed with inclined teeth for the purpose stated, and a cement gauge or clearer constructed to permit a relatively larger take-up of cement by the outer portion of said roll, the incline of the teeth on said roll being such as to influence the cement inward of the roll.

In testimony whereof, I have signed my name to this specification.

WALTER P. OSGOOD.
